(57) **CLAIM**

We claim the ornamental design for a shoe outsole, showing our new design.

DESCRIPTION

FIG. 1 is a bottom plan view of a shoe outsole showing our new design;

FIG. 2 is a right side elevational view thereof;

FIG. 3 is a left side elevational view thereof;

FIG. 4 is a front elevational view thereof; and,

FIG. 5 is a rear elevational view thereof.

The phantom lines showing portions of a shoe in FIGS. 1–5 are for illustrative purposes only and form no part of the claimed design.
